UNITED STATES PATENT OFFICE.

CHARLES H. FLETCHER, OF BEAVER FALLS, PENNSYLVANIA.

BROILER.

1,096,029.

Specification of Letters Patent. Patented May 12, 1914.

Application filed October 23, 1911. Serial No. 656,166.

To all whom it may concern:

Be it known that I, CHARLES H. FLETCHER, a citizen of the United States, residing at Beaver Falls, in the county of Beaver and State of Pennsylvania, have invented certain new and useful Improvements in Broilers, of which the following is a specification.

This invention relates to improvements in broilers and has for its object to provide a simple, inexpensive, and highly efficient broiler.

The leading feature of my invention consists in providing a grate which can be readily moved out of a heating chamber by an operator without applying manual power to the grate itself.

A further object of my invention consists in providing means for automatically shutting off the flow of a heating fluid into the heating chamber, when the grate is being moved out of the heating chamber.

With the above and other objects in view my invention consists in the combination, arrangement, and details of construction disclosed in the specification and drawings and then more particularly pointed out in the appended claims.

In the drawings wherein similar reference characters designate similar parts throughout the respective views, Figure 1 is a vertical elevation, partly in section, of my invention showing the interior of the heating chamber, Fig. 2 is a cross-sectional view of the carriage runway and a part of the table, Fig. 3 is a bottom plan view of the device, Fig. 4 is a detail view of the grate carriage and the spring put under tension as the carriage is moved, Fig. 5 is a longitudinal plan view, partly in section of the device, taken on the line Y—Y of Fig. 1, Fig. 6 is a side elevation of the lower part of my invention, Fig. 7 is an end view of the movable grate showing one section in released position, Fig. 8 is a detail view of the grate carriage movable in opposition to a weight, Fig. 9 is a detail view of the grate holder in which the grate is shown tilted, Fig. 10 is a detail view of a latch for holding the grate in the heating chamber, Fig. 11 is a detail top plan view of the member arranged to open and partially close the valve controlling the passage of fluid to the jet pipes in the heating chamber, Fig. 12 is a detail elevation of the grate held in normal position outside of the

heating chamber, and Fig. 13 is a front end elevation of the device.

Referring to the accompanying drawings, a heating chamber is designated 1, resting on the offsets 66 formed upon the legs 2. A table 3 forms a part and extension of the heating chamber 1, said table having a housing 4 which supports it. Two spaced apart walls 6 and 7 extend around three sides of the heating chamber and inclose sheets of asbestos 5. A lid 8 is mounted on the top of the heating chamber and a chimney 9 leads out of said lid. Formed in walls 6 and 7 and in the asbestos sheet 5 are registering vent ports 10. A door 11 is hinged at 12 to the heating chamber and has an asbestos sheet 13 suitably inclosed therein. Vertically disposed pipes 14 are oppositely-arranged preferably at the corners of the sides of the heating chamber and are connected by a vertically disposed series of spaced-apart pipes 15, having each a plurality of jet openings 16 for spraying the chamber with flames toward the center of said chamber. The pipes 14 extend below the floor 17 of the heating chamber and the two foremost of said pipes 14 are connected by the transverse pipe 18 with which connects a longitudinally extending pipe 19 whose inlet end 25 may be connected to any gas supply.

The pipe 19 is disposed beneath the table 3 and passes through the depending housing 4 where a suitable cut-off valve is disposed connected to a vertical stem 20 revoluble in a coupling 21 and carrying at its top a wheel or disk 21' having an opening through which projects the offset 22 of a longitudinally-extending rod 23. This rod 23 passes through a casing 24 and has an offset 31 projecting into an opening in a wheel or disk 32 rotatably mounted on a stud 33 carried in a bracket 34 horizontally disposed at the rear of the heating chamber. The casing 24 extends under the table and the heating chamber, and both at its top 29 and bottom 27 is formed with longitudinal slots 30, and 28 respectively, the sides of said casing being designated 25 and 26 respectively. A grate carriage is arranged to move upon the bottom 27 of casing 24, and it is composed of a bottom 37, two pairs of oppositely-arranged wheels or rollers 39' mounted on axles 39 and 40 respectively disposed transversely in depending bearings 41 carried by the bot-

tom 37. A plurality of posts 42 connect the bottom of this carriage with the top 43, the top 43 rising above the top 29 of casing 24, and all of said posts 42 being disposed in the slot 30. A brace member 44 comprising the folds 45 and 46 is suitably mounted upon the top plate 43.

Mounted upon the folds 45 and 46 of brace member 44 is an upright U-shaped frame 47 and upon trunnions 48 secured to said frame is mounted a rectangular grate 53 having the spaced apart longitudinal grate bars 52, said grate 53 being held against displacement by the nuts 50. To hold the steaks or meat upon this grate a latticed member 40' is provided consisting of longitudinal bars 54 and 55 and transverse rods 51. This latticed member 40' is placed against the grate 53 over the meat, and may be held thereover by any suitable means such as by a rod 58 having a part 59 swiveling in one of the edges of grate 53. When member 40' is laid flat upon the meat this rod 58 is swiveled so as to bear bodily upon this member, and the terminal offset 59 formed on the free end of rod 58 may be received under the offset 57 of the catch 56 secured upon another edge of grate 53, and in this way the latticed member 40' will remain in position. The carriage has a vertical stud 36 under its bottom with which is adapted to engage the lugs 35 spaced apart upon the rod 23 for a purpose to be described.

The carriage 38' is intended to move into the heating chamber under suitable resistance from a flexible medium so that the tendency will be to normally hold it at the foremost end of the longitudinal slot 30 in the table 3. In Figs. 3 and 4 a retractile longitudinally extending spring 59' is used which is fixed to a stud 60 mounted on the bracket 34 at the rear of the heater and has its free end connected to a cord or cable 61 passing over a pulley 62 revolvably mounted on an axle 63 which is held between the opposed walls of the housing 4 and is disposed at right angles to the body of the spring. The free end of the cord 61 is fastened to a lug 64 depending from the bottom sill 37 of the carriage. However, a weight 65 may be utilized, as shown in Fig. 8, it being understood that the entire device will be secured to any suitable support such as a table and held in elevated position to afford convenience to the user; in this way the weight 64 may descend by gravity toward the floor and thereby restore the carriage 38' to normal position, the cord 67 to which the weight is attached passing over the pulley 62.

To hold the grate 53 outside of the heating chamber it is only necessary to swivel it on the trunnions 48 to horizontal position, as shown in Fig. 12 so that the rear end

of said grate 53 may be received in the recess 68 of a stop 69 projecting forwardly of one side of the heating chamber. In this position the carriage will have moved slightly inward from the forward end of the longitudinal slot 30 and when it is moved to the end thereof the member 53 will be released from stop 69 and may be tilted to its vertical position to be impelled into said heating chamber.

At the rear end of the heating chamber and mounted at one side 26 of the casing 24 the latch mechanism is disposed, which is designed to check the reverse movement of the grates on the carriage 38' after the latter shall have been moved into the heating chamber 1, thus serving to counterpoise the weight 65. A stout wire member 71 of the desired resiliency is bent into two parts 72 and 73, the loop portion 74 common to said parts 72 and 73 being received in the lug 75 and held against displacement by a pin 76, the lug and pin being mounted on the wall 26. A bent offset 74' is formed on part 72 of wire 71 and projects into the opening 75' in wall 26, this offset projecting in the path of movement of the rearmost post 42 of the carriage 38'. Above the part 72 is a lug 76' projecting from wall 26 and carrying a bolt 77 embraced by the eye 77' formed upon a coupling member 79 connected respectively to the offset 72 and by means of a hook 80 to a flexible member or cord 81 adapted to be wound about a drum or stud 82 having its bearings in the lower end 83 of a bracket 84 dependingly carried by the table 3, said stud projecting therethrough and formed with an operating crank 84'.

Under the heating chamber is a chamber 85, which is provided with a sight opening 87, barred by a screen 88. A grease or drip pan 90 is received in a passage way 89 formed in a chamber 85, said pan being removable by means of the handle 91. It will be noted that the grease and juice emitted by the steak to be broiled will drip through the slots 30 and 28 of casing 24 into the grease pan 90 disposed under the heating chamber.

The broiler herein-described will be used as follows:—Fig. 12 shows the grate 53 held in horizontal position. It may now receive the steaks to be broiled, and when the latticed member 40' shall have been placed over said steaks and locked by means of rod 58, as before explained, grate 53 may be pushed backward against the tension either of the spring 59 or weight 65 into the heating chamber as far as it can be moved. It is obvious that carriage 38' in following the movement of the grate 53 will move to a position where one of its posts 42 will engage with the bent offset 74', thereby forcing it inward through the opening 75' in the

wall 26, as shown in dotted lines in Fig. 10. This is intended to enable said stud to move by said offset 74', and when this has been effected said offset 74' will be restored to its 5 normal position and the post 42 will bear against it, thereby preventing the carriage from moving. As said carriage is moving into the heating chamber its vertical lug 36 will engage with the rear lug 35 carried by 10 the rod 23 thereby moving said rod and opening the valve controlled by the valve stem 20 through the superposed disk 21' on which the hook 22 of rod 23 projects. Gas will then commence to flow into the inlet 15 pipe 19 thence through the transverse pipe 18 and upwardly through the upstanding pipes 14 and by means of the jet pipes 15 will furnish the degree of heat needed for broiling meat in the heating chamber. 20 While broiling takes place in the heating chamber 1 the juices will drop through the slots 30 and 28 into the grease pan 90 at the bottom of the chamber 85. The fumes of combustion may escape through the chimney 25 9 in the lid 8 while air may enter through the port 10 in the back of the heating chamber 1.

When it is desired to move the grate 53 out of the heating chamber 1 the door 11 will 30 be opened. The operator turns crank handle 84' which projects over table 3, thereby causing the flexible member 81 to be wound upon the drum or stud 82 in the bracket 84 which will move the coupling member 79 on the 35 pivot 77 in the direction shown in dotted lines in Fig. 10, in consequence of which the coupling member 79 will retract the bent offset 74' of the stout wire 71 to disengage it from the rearmost post 42 of the carriage 40 38'. As soon as this has been effected the carriage 38' will automatically be impelled to a position outside of the heating chamber, through the instrumentality of the retractile spring 59' which will recoil or by the weight 45 65 which will descend by gravity. In thus moving out of the heating chamber, the vertical lug 36 carried by the carriage will move away from the rearmost lug 35 on the rod 23, this lug 35 having already been 50 moved to the position shown in dotted lines in Fig. 11, and before it comes to rest said vertical lug 36 will engage the other lug 35 on rod 23, which has already been moved to the position shown in dotted lines in Fig. 55 11, and in this way the last-named lug 35 will be restored to normal position shown in full lines in Fig. 11, and thereby turning down low, by means of the rod 23 and valve stem 20, the inflow of gas and checking said 60 inflow. In this way all waste of gas is avoided. The broiled steaks may then be removed, after grate 53 is again placed in such a position that stop 54 will hold it in horizontal position.

65 Numerous modifications may be resorted

to in practice without departing in principle from the details of construction herein described.

I claim and desire to secure by Letters Patent:

1. A heating chamber having oppositely disposed spaced apart vertically arranged burners therein, a carriage adapted to pass between said burners, a broiler on said carriage, said broiler being mounted pivotally 70 on said carriage, said carriage adapted to hold said broiler in a vertical position, and a table connected exteriorly to said heating chamber over which table said carriage is 75 movable.

2. A heating chamber having oppositely disposed spaced apart vertically arranged burners therein, a carriage adapted to pass between said burners, a broiler on said carriage, said broiler being mounted pivotally 80 on said carriage, said carriage adapted to hold said broiler in a vertical position, said heating chamber having a floor and a table integral with the outside of said heating chamber over which table said carriage is 85 movable, the surface of said table being on a plane with the floor of said heating chamber.

3. A heating chamber having oppositely disposed, spaced apart vertically arranged 90 burners therein, a carriage adapted to pass between said burners, a broiler on said carriage, said broiler being mounted pivotally on said carriage, said carriage adapted to hold said broiler in a vertical position, a 95 table connected to said heating chamber, said heating chamber having a floor, the surface of said table being on a plane with the floor of said heating chamber, said floor and table being formed with a slot, and a track 100 for said carriage arranged below the surface of said table and said floor and on a line with said slot.

4. A heating chamber having oppositely disposed, spaced apart vertically arranged 110 burners therein, a carriage adapted to pass between said burners, a broiler on said carriage, said broiler being mounted pivotally on said carriage, said heating chamber being formed with a floor, said carriage adapted 115 to hold said broiler in a vertical position, a table connected to said heating chamber, the surface of said table being on a plane with the floor of said heating chamber, said floor and said table being formed with a slot, and a track for said carriage arranged below the surface of said table and said heating chamber and on a line with said slot, said carriage extending partially into said slot whereby it 120 will be held in a vertical position by the 125 edges of said slot.

5. A heating chamber having oppositely disposed spaced apart vertically arranged burners therein, a carriage adapted to pass between said burners, a broiler on said car- 130

riage, said broiler being mounted pivotally on said carriage, said carriage adapted to hold said broiler in a vertical position, a table connected to said heating chamber, 5 said heating chamber being formed with a floor, the surface of said table being on a plane with the floor of said heating chamber, said floor and table being formed with a slot, a track for said carriage arranged below the surface of said table and said floor 10 and on a line with said slot, said carriage extending partially into said slot whereby it will be held in a vertical position by the edges of said slot, said carriage being spring actuated whereby it will be held normally 15 out of said heating chamber.

6. A heating chamber having oppositely disposed spaced apart vertically arranged burners therein, a carriage adapted to pass 20 between said burners, a broiler on said carriage, said broiler being mounted pivotally on said carriage, said carriage adapted to hold said broiler in a vertical position, a table connected to said heating chamber, said 25 heating chamber formed with a floor, the surface of said table being on a plane with said floor, said floor and said table being formed with a slot, a track for said carriage below the surface of said table and said floor 30 and on a line with said slot, said carriage extending partially into said slot whereby it will be held in a vertical position by the edges of said slot, said carriage being spring actuated whereby it will be held normally 35 out of said heating chamber and means for locking said carriage within said heating chamber.

7. A heating chamber having oppositely disposed spaced-apart vertically arranged 40 burners therein, a carriage adapted to pass between said burners, a broiler on said carriage, said broiler being mounted pivotally on said carriage, said carriage adapted to hold said broiler in a vertical position, a 45 table connected to said heating chamber, said heating chamber being formed with a floor, the surface of said table being on a plane with said floor, said floor and said table being formed with a slot, a track for 50 said carriage arranged below the surface of said table and said floor, and being on a line with said slot, said carriage extending partially into said slot whereby it will be held in a vertical position by the edges of said 55 slot, said carriage being spring actuated whereby it will be held normally out of said heating chamber, and means for locking said carriage within said heating chamber, and a gas supply for said burners, said carriage 60 adapted to regulate the supply of gas to said burners.

8. A heating chamber having oppositely disposed spaced apart vertically arranged 65 burners therein, a carriage adapted to pass between said burners, a broiler on said car-

riage, said broiler being mounted pivotally on said carriage, means whereby said carriage may hold said broiler in a vertical position, a table connected to said chamber, the surface of said table being on a plane 70 with the floor of said chamber, said floor and said table having a slot, a track for said carriage arranged below the surface of said table and the floor of said chamber and in vertical alinement with said slot, said carriage extending partially into said slot whereby it will be held in a vertical position by the edges of said slot, spring means arranged to hold said carriage normally out of said chamber, means for locking said carriage within said chamber, a gas supply for 75 said burners, means whereby said carriage may regulate the supply of gas to said burners, and means for releasing said lock.

9. A heating chamber having an oppositely arranged series of pipes forming 80 burners, a carriage adapted to move alongside of said pipes, a broiler carried by said carriage and being vertically mounted thereupon, a table disposed forwardly of said chamber and on a plane with the floor thereof, said table and floor being formed with a slot, a track disposed longitudinally below said table and a floor upon which said carriage moves, a guide rod carried by said 85 carriage projecting into said slot whereby it will be held in vertical position by the edges of said slot, means whereby said carriage will be held normally outside of said chamber, means whereby said carriage may 90 be locked within said chamber, said carriage being impellable automatically out of said chamber when said lock is released, means whereby said carriage may regulate the gas 95 in said pipes, means for releasing said lock, and means for actuating said last named 100 means.

10. The described device embracing a heating chamber having vertically arranged oppositely disposed burners, a table having 110 a surface alining with the floor of said chamber, said table and floor having a slot, a carriage movably mounted within said slot, a normally vertically disposed broiler pivotally mounted upon said carriage, and 115 means whereby said carriage may be actuated.

11. The described device embracing a heating chamber having vertically arranged oppositely disposed burners, a table having 120 a surface alining with the floor of said chamber, said table and floor having a slot, a carriage movably mounted within said slot, a normally vertically disposed broiler pivotally mounted upon said carriage, means 125 whereby said carriage may be actuated, and means for locking said carriage within said chamber.

12. The described device embracing a heating chamber having vertically arranged 130

- oppositely disposed burners, a table having a surface alining with the floor of said chamber, said table and floor having a slot, a carriage movably mounted within said slot, a normally vertically disposed broiler pivotally mounted upon said carriage, means whereby said carriage may be actuated, means for locking said carriage within said chamber, and means whereby said carriage will be automatically removed from said chamber when said lock is released.
13. A heating chamber having vertically arranged burners therein, a carriage adapted to move within said chamber, a pivotally mounted broiler on said carriage, a track upon which said carriage is adapted to travel, and a floor for said chamber having a slot therein, said track being located below said slot.
14. A heating chamber having vertically arranged burners therein, a carriage adapted to move within said chamber, a pivotally mounted broiler on said carriage, a track upon which said carriage is adapted to travel, and a floor for said chamber having a slot therein, said track being located below said slot and in alinement with said slot, said floor and track extending beyond said chamber.
15. A heating chamber having vertically arranged burners therein, a carriage adapted to move within said chamber, a pivotally mounted broiler on said carriage, a track upon which said carriage is adapted to travel, and a floor for said chamber having a slot therein, said track being located below said slot and in alinement with said slot, said floor and track extending beyond said chamber.
16. A heating chamber having vertically arranged burners therein, a carriage adapted to move within said chamber, a pivotally mounted broiler on said carriage, and a gas supply source for said burners, the movement of said carriage adapted to control the flow of said gas.
17. A heating chamber having vertically arranged burners therein, a carriage adapted to move within said chamber, a pivotally mounted broiler on said carriage, a track upon which said carriage is adapted to travel, and a floor for said chamber having a slot therein, said track being located below said slot and in alinement with said slot, said floor and track extending beyond said chamber, and a gas supply source for said burner and means whereby the movement of said carriage will control the supply of said gas.
18. A heating chamber having vertically arranged burners therein, a carriage adapted to move within said chamber, a pivotally mounted broiler on said carriage, a track upon which said carriage is adapted to travel, and a floor for said chamber having a slot therein, said track being located below said slot and in alinement with said slot, said floor and track extending beyond said chamber, a gas supply source for said burner, means whereby the movement of said carriage will control the supply of said gas, and means whereby said carriage may be actuated.

In testimony whereof I affix my signature in presence of two witnesses.

CHAS. H. FLETCHER.
